UNITED STATES PATENT OFFICE.

BERNT HESTNESS, OF DONALDA, ALBERTA, CANADA.

SELF-CLEANING HARROW.

1,249,395.

Specification of Letters Patent. Patented Dec. 11, 1917.

Application filed November 20, 1916. Serial No. 132,491.

To all whom it may concern:

Be it known that I, BERNT HESTNESS, a subject of the King of Great Britain, and resident of Donalda, in the Province of Alberta, Dominion of Canada, have invented 5 certain new and useful Improvements in Self-Cleaning Harrows, of which the following is a specification.

This invention relates to improvements in 10 harrows and the objects of the invention are to render the harrow self cleaning, to facilitate adjusting the teeth of the harrow, and generally to adapt the several parts to better perform the functions required of them.

15 With the above and other objects in view, the invention consists essentially of the improved construction particularly described and set forth in the following specification and accompanying drawings forming part 20 of the same.

In the drawings,

Figure 1 is a perspective view of one section of the harrow.

Fig. 2 is a longitudinal section of the complete machine.

Fig. 3 is a longitudinal section of one of the sections of the harrow.

Fig. 4 is a transverse section through the center member of one of the harrow sections.

30 Fig. 5 is a fragmentary longitudinal section of the center member of the harrow section.

Fig. 6 is a fragmentary end view of the harrow.

35 Like characters of reference refer to like parts in the several figures.

Referring to the drawings, A represents the harrow comprising the sill 10 to the forward end of which the beam 11 is attached, while the rear end is supported by the ground wheels 12 rotatably mounted on the axle 13.

40 Operatively mounted on the sill 10 above the axle 13 is a driver seat 14, while intermediate of the sills standards 15 are provided carrying transverse beams 16 from which the pulleys 17 are rotatably supported, while below the sill a transversely extending shaft 18 is rotatably mounted carrying a plurality of pulleys 19 the object of 50 which will be made clear hereafter.

A rectangular frame 20 is operatively connected to the beam 10 by chains 21, the

said frame being constructed of angle iron members 22 and 23, the latter of which are 55 connected intermediate of their length by a pair of spaced channels 24.

Transversely extending spindles 25 are journaled in the members 22 and 24 and are provided with cams 26 located between the 60 spaced channels 24 while between the members 22 and 24 teeth 27 are provided having the bosses 30 rigidly mounted on the said spindles.

Co-acting with the cams 25 are tappets 65 31 pivotally mounted to the guide member 32 slidably mounted on the upper face of the channel 24 and retained in position by the guard members 33, the lower end of the tappets engaging with the cams while the upper 70 ends are pivotally attached to the rod 34, the front of which is connected by a spring 35 to the frame 20, the rear of the rod being connected to the flexible member 36 which passes around the pulleys 19 and 17 and is 75 connected to a foot rest 37 in front of the driver seat 14.

The guide member 32 is capable of longitudinal adjustment and to this end I provide a lever 38 pivotally mounted to the channel 80 member 24 and connected intermediate of its length to the guide member 32, the said lever being provided with a detent 39 co-acting with the quadrant 40 mounted in the frame 20.

85 The assembly of the several parts will be readily understood from the foregoing description.

When the harrow is in use, horse traction is attached to the beam 11 and during the 90 forward motion of the machine the teeth 27 pulverize the ground.

It is understood that rubbish will collect on the teeth during this operation and when the driver desires to clean the teeth he applies pressure to the foot rest 37, the motion being transmitted through the flexible member 36 to the rod 34 which is displaced longitudinally permitting the lower end of the tappets 31 to be disengaged from the cam 95 26, thereby allowing the spindles 25 to rotate so that fresh teeth 27 engage the ground and the rubbish collected by the other teeth is left in wind-rows.

Should it be found advisable at any time 105 to alter the inclination of the teeth 27 this

may be done by actuating the lever 38 and adjusting the position of the guide member 32 so that the tappets 31 will be engaged with the cams 25 at a different position during the rotation of the spindles 25.

From this description it will be seen that I have invented a harrow which can be advantageously utilized by farmers and in which the teeth are self cleaning, the arrangement being such that the rubbish collected is deposited in wind rows, while the inclination of the teeth can be adjusted to suit the type of soil under cultivation.

As many changes could be made in the above construction, and many apparently widely different embodiments of my invention, within the scope of the claim, constructed without departing from the spirit or scope thereof, it is intended that all matter contained in the accompanying speci-

fication and drawings shall be interpreted as illustrative and not in a limiting sense.

What I claim as my invention is:

A harrow of the class described comprising a frame, spindles rotatably mounted in the frame, teeth on the spindles, cams on the spindles, guide means located above the said cams, tappets carried by the guide means and means for actuating the tappets comprising a reciprocating rod engaging said tappets, a compressible member, a flexible connection between the member and the rod, and a spring for maintaining the rod in a normally operative position.

In witness whereof I have hereunto set my hand in the presence of two witnesses.

BERNT HESTNESS.
